JAW CRUSHERS

Frank H. Dougherty, Lancaster, Pa.

Application January 6, 1953, Serial No. 329,784

26 Claims. (Cl. 241—264)

This invention relates to improvements in apparatus for crushing relatively hard materials such as rock, ore and the like, and is more particularly directed to crushing apparatus of the class known as jaw crushers.

Conventional jaw crushers comprise essentially a rigid crushing face, a usually hinged movable jaw, and an eccentric motion for actuating the hinged jaw toward and away from the rigid crushing face. In one type, the hinged jaw swings about an overhead axis, and in another type about a bottom axis. Usually, the eccentric motion is transmitted from an eccentric mounted on a main or drive shaft by a pitman, or from a similarly mounted cam by a hinged lever, to a toggle which acts through the free end of the hinged jaw to impart the tremendous pressure on the material entering the crushing chamber required for its reduction. There are, of course, numerous variations of the aforesaid crusher design; but all jaw crushers have the common feature that the force exerted against the shaft by eccentric or cam throw, and which is a direct function of the crushing pressure developed during a crushing operation, is applied more or less uni-directionally to the shaft, that is to say, to one side thereof, and thus causes or tends to cause shaft deflection. When it is further considered that the main bearings in which the eccentric or cam shaft is journaled are required not only to supply the thrust or reaction force enabling the shaft to withstand such uni-directionally applied high force, but also to take a continuous succession of shock forces accompanying the intermittent breaking that occurs during a normal crushing operation, it will readily be appreciated that shaft and bearing failures are not infrequent and that, even in the absence of actual failures, a large-size shaft and massive bearings are required, and the bearings usually run hot, thus introducing serious lubricating problems.

Broadly stated, an object of the invention is to provide an improved jaw crusher characterized by a novel cam motion system providing high mechanical advantage, and which further protects the main or cam shaft against deflection, while at the same time relieving the main bearings of the requirement of providing the thrust reaction for the crushing loads transmitted to the shaft by the throw of the cam.

Another object of the invention is the provision of an improved jaw crusher, wherein the defective force applied to the main shaft consequent to cam throw is effectively neutralized by a substantially equal force applied to the shaft in opposite direction.

Yet another object of the invention is the provision of an improved jaw crusher employing a novel cam motion system which itself supplies the thrust reaction for the forces transmitted to the cam shaft consequent to the crushing operation.

Still another object of the invention is the provision of an improved jaw crusher characterized by a cam motion system so constructed and arranged as to effect a subdivision of the high crushing loads occurring during each actuation of the movable jaw and the delivery of the

2

subdivided loads to the cam shaft in the form of opposing forces which effect a squeezing action on the shaft rather than a deflection thereof.

A further object of the invention is the provision of an improved jaw crusher wherein the cam motion is provided by two toggle systems arranged symmetrically to opposite sides of the cam shaft and which are of substantially similar size and weight, thereby to insure maximum balance, as well as favorable distribution of the crushing loads transmitted to the shaft.

Another object of the invention is the provision of an improved jaw crusher characterized by a cam motion which effects actuation of the moving jaw with substantially bodily linear motion rather than with the conventional swinging motion, thus to eliminate jaw wear caused by relative vertical movement of the jaws, as in conventional hinged or swinging jaw crushers.

A still further object of the invention is the provision of an improved multi-jaw crusher, wherein several pairs or sets of jaw faces are positioned and arranged so as to provide several independent crushing chambers which can be fed from the same common hopper at the same time yet independently of one another.

Yet another object of the invention is the provision of an improved multi-jaw crusher employing a sizing screen which slopes in two directions, the arrangement of jaw sets and sizing screen being such that the material flowing from one set of jaws passes to the screen, which diverts the material requiring further reduction to one or the other of the remaining jaw sets.

More detailed objects of the invention are to provide an improved jaw crusher characterized by simple, sturdy and economical construction, by simple and cheap means for mounting the movable jaw for substantially straight-line, horizontal movement, and by safety features permitting the movable jaw to give, as when tramp iron is encountered.

The above and other objects and features of advantage of a jaw crusher according to this invention will appear in the following detailed description thereof, reference being had to the accompanying drawings illustrating various physical embodiments which the invention may take, in which—

Fig. 1 is a longitudinal section taken through one form of jaw crusher according to the invention;

Fig. 2 is a section taken along line 2—2 of Fig. 1;

Fig. 3 is a view similar to Fig. 1, but illustrating a modified cam motion and toggle system for actuating the movable jaw;

Fig. 4 is a longitudinal section taken through the crushing chamber of a multi-jaw crusher illustrating the application of a cam motion or toggle system according to the invention to such a construction;

Fig. 5 is a view similar to Fig. 4, illustrating a further application of the principles of this invention to a crusher of the type known as a three-jaw crusher incorporating a sizing screen;

Fig. 6 is a detail view looking into one of the movable jaw supporting means; and

Fig. 7 is a section taken along line 7—7 of Fig. 6.

Referring to Figs. 1, 2, 6 and 7, illustrating a jaw crusher, employing one form of cam motion system for actuating the movable jaw according to this invention, reference numeral 10 generally indicates a crusher frame which may comprise side members 11 and 12 (Fig. 2), and cross beams extending therebetween and providing a frame end member 13, the latter supporting, in adjustably inclined position within the frame enclosure, a fixed jaw assembly generally designated 14. Illustratively, said jaw assembly comprises a transversely extending supporting plate 15 and hard-metal wear plates 16, 16a secured thereto, which together constitute a fixed

crushing face 17. Inasmuch as the constructional details of the fixed jaw assembly and its mounting are conventional, no detailed description thereof is given.

Cooperating with the fixed jaw so as to form therewith a crushing chamber is a movable jaw assembly 18 shown to be constituted by a transverse supporting plate 19 and hard-metal wear plates 20, 20a secured thereto and which together form a movable crushing face 17A. The supporting plate may be structurally reinforced by rearwardly extending ribs 21 giving it the necessary strength and rigidity, of which the two end-most ribs may function as the side plates for the movable jaw assembly.

According to one feature of the invention, simple and inexpensive means are provided for suspending the movable jaw assembly 18, which for convenience will be hereinafter referred to as the "movable jaw," from the frame and within the frame enclosure. Referring to Figs. 6 and 7 illustrating one of the supporting means, there being two such supporting means one for each side of the movable jaw, such may comprise an upright supporting arm or link 22 whose upper and lower end edges are formed as arcs of a circle struck from a center located at the link mid-point. The link 22 is normally vertically disposed and extends between vertically related upper and lower horizontal surfaces, the upper being the under face of an upper block 23 which is secured as by welding to the end plate of the movable jaw, and the lower horizontal surface being the upper face of a lower block 24 secured as by bolts 25 to the horizontal bottom edge of an opening 26 provided in the adjacent side member of the frame. By reference to Fig. 7, it will be observed that the upper block 23 is offset to extend into the plane of the frame opening 26, thereby to maintain the link 22 in the vertical plane of said opening. Preferably, retaining plates such as the plate 27 secured to the upper block 23, or other appropriate retaining means, are employed to confine movement of the link in said plane. By the described arrangement, the weight of the movable jaw 18 is transmitted to the side members 11 and 12 of the main frame 10 through the pair of intermediate supporting links 22. It will also be understood that because of their arcuate end edges said links may "roll" in the manner of a wheel on the aforesaid upper and lower horizontal surfaces as provided by the blocks 23, 24. Hence, upon a push or pull force being applied top and bottom to the movable jaw 18, it moves bodily on the supporting links with horizontal linear motion, and this is also substantially the case when the push or pull force is applied alternately top and bottom to the movable jaw.

As forecast above, the invention also provides a novel cam-motion system for translating cam throw into horizontal linear or substantially linear movement of the movable jaw 18 and which is further specially designed so as to protect the cam shaft against deflection and to relieve to a substantial degree the main or cam shaft bearings of the requirement of supplying the thrust reaction for the high crushing loads transmitted to said shaft. One form of such a cam motion is illustrated in Figs. 1 and 2, wherein reference numeral 28 designates the drive or cam shaft which is journaled for rotation in main bearings 29, 30 mounted in the frame side members 11, 12. The drive shaft may mount a fly-wheel 31 keyed or otherwise affixed to a projecting end of the shaft and which functions to smooth out irregular shaft motion, and the shaft is driven from its other end through a suitable source of power (not shown). The cam which generates the cam motion responsively to rotation of the shaft may take form of a single-lobe cam 32 carried by the shaft 28 and preferably formed integral therewith, as shown in Fig. 2.

According to the invention, two toggle mechanisms designated T₁ and T₂ disposed symmetrically to opposite sides of the shaft 28, are employed to translate throw of the cam 32 into movement of the movable jaw 18

toward the fixed jaw 14. More particularly, one toggle T₁ is disposed to the upper side of the shaft and the other toggle T₂ is disposed to the lower side of the shaft. The upper toggle T₁ illustratively comprises two toggle arms in the form of solid, transversely extending plates 33, 34, the forward end of the front toggle arm 33 engaging on a transversely extending seat affixed in a transversely extending seat block 35 carried by and extending from the rear face of the movable jaw 18 adjacent its top end. The rear end of said toggle arm 33 has a block-like section, and affixed to its rear side face is a transversely extending seat 36 for the front end of the companion toggle arm 34, the rear end of which engages on a transversely extending seat affixed in a transversely extending seat block 37 carried by an upper transverse beam 38 extending between the frame side members 11, 12.

Secured to the under flat face of the block-like rear end of the toggle arm 33 as by bolts is a transversely extending hanger-type support 39 for a non-rotary axle shaft 40 on which a transverse series of cam followers 41 are journaled for rotation in bearings. As seen in Fig. 2, the support 39 preferably incorporates between its end plates a plurality of partition plates 39a spaced to accommodate the cam followers 41, said plates being shaped along their lower end edges to embrace the upper periphery of the axle shaft 40 and thus serving to buttress the shaft from above at a plurality of points along its length. The described axle shaft mounting provides a simple yet extremely rigid form of axle mount for the rotatable cam followers 41, which latter normally bear on the drive shaft 28, but are engaged by the cam 32 once per revolution of said shaft. As is well understood, such engagement results in the toggle arms 33, 34 being "straightened," i. e. moving upwardly to a substantially straight-line relation, thereby to exert a thrust force against the upper end of the movable jaw 18 in direction as to actuate it toward the fixed jaw 14.

The lower toggle mechanism T₂ illustratively comprises toggle arms 42, 43, also having the form of transversely extending plates, of which the forward end of the toggle arm 42 engages on a seat affixed in a transversely extending seat block 44 secured as by welding to a rigid thrust-transmitting hollow box-beam 45 which extends longitudinally-rearwardly from the lower end of the movable jaw 18. The rear end of the toggle arm 42 is formed with heavy block-section providing a substantially rear vertical face which mounts a transversely extending seat 46 for the forward end of the companion toggle arm 43, the other end of which engages on a transverse seat affixed in a transversely extending seat block 47 secured to a lower transverse beam 48 extending between the frame side members.

As illustrated, the block-like rear end of the toggle arm 42 is of two-part construction, the parts 42a, 42b thereof being adapted to slide relatively of one another on a common meeting surface indicated at 42c, and which is preferably inclined. In normal operation, said block parts 42a, 42b are yieldably held against relative sliding movement as by means of elongated bolts 49 extending longitudinally through both said parts and compression springs 50 mounted thereon, the springs being reactive against the rear end face of the block part 42a and adjusting nuts 51 threaded on said bolts. The purpose of the two-part slidable construction and of the yielding connection between the parts 42a, 42b will be explained later.

Secured to the top flat face of the relatively upper block part 42b of the toggle arm 42 is a transversely extending support 53 for a non-rotary axle shaft 54 carrying a transverse series of cam followers 55 journaled for rotation on bearings carried by said shaft. The support 53 is a replica of the support 39, 39a except that its position is turned 180°, thus to expose the upper periphery of the cam followers 55 to the cam 32. Thus, the cam followers 55 are engaged by the cam once per revolution

of the shaft 28 and it will be observed that such engagement occurs at intervals of approximately 180° of shaft rotation with respect to engagement of the cam 32 with the cam followers 41 of the upper toggle T₁. The aforesaid engagement of cam 32 with the cam followers 55 results in downward movement of the toggle arms 42, 43 to substantially straight line relation, i. e. straightening of the toggle, and hence in a thrust force being applied to the bottom end of the movable jaw 18 in direction as to cause it to move towards the fixed jaw 14.

The return stroke of the upper end of the movable jaw 18, following its actuation by the upper toggle mechanism T₁, is effected as by springs 58 mounted on the projecting rear ends of bolts 59 extending between the upper corners of the movable jaw and the ends of the aforesaid upper transverse beam 38. Similarly, the return stroke of the lower end of the movable jaw 18 is effected by springs 61 on the projecting rear ends of longitudinal bolts 62 which are disposed outwardly of the frame side members 11 and 12 and extend between the lower end of the movable jaw and the aforesaid lower transverse beam 48 extending between the side frame members.

Preferably, the connection between the forward, or head ends of the bolts 62 and the lower end of the movable jaw 18 is such as to provide for limited movement of the said lower end independently of the lower toggle mechanism T₂ and the retracting springs 61, for example, during a repair operation. For this purpose, the head ends of the bolts 62 are each formed as a clevis 63 and said clevis ends are connected as by vertical bolts 64 (Fig. 1) to the ends of a transverse bar 65 extending through and affixed to the box beam 45. Said bar ends project through slot-like openings 66 provided therefor in the lower frame side members 11, 12, said side frame members also mounting external brackets through which stop bolts 67 are threaded. Said stop bolts provide adjustable stops for the ends of the transverse bar 65 which permit some movement thereof along the frame openings 66 in leftwise direction (Fig. 1) over and above that resulting from straightening of the lower toggle 12 of the stop bolts, but by proper adjustment of the stop bolts, this movement will always be less than that which would enable the lower toggle parts to disengage and drop away from one another when the tension of springs 61 is released.

The toggle mechanisms T₁ and T₂ are yieldably connected by a spring form of connection generally designated 68, which assists in maintaining both toggle mechanisms in their relatively retracted position, and thereby the cam followers 41, 55 in engagement with the shaft 28 and/or its cam 32. Additional springs 69, 70 (Fig. 2) exert an upward resilient thrust on the lower toggle mechanism T₂ and serve to take a substantial portion of the weight of the parts making up the same. Thus, the springs 69, 70, the spring link connection 68 and the retracting springs 61 all contribute to maintaining the lower toggle T₂ in its retracted position, thereby positively insuring engagement of the cam followers 55 thereof with the shaft 28 and/or its cam 32.

The operation and functioning of the above described toggle system will, it is believed, be clear to persons skilled in the art. Briefly, rotation of the drive shaft 28 results in the toggle mechanisms T₁ and T₂ being alternately spread or straightened at intervals of 180° of shaft rotation. When the toggle T₁ is straightened, and considering that the lower toggle T₂ is now at rest and that its point of connection with the movable jaw provides a fulcrum point for the latter's movement, a heavy thrust is applied to the upper end of the movable jaw 18 in direction causing it to move towards the fixed jaw and thereby to exert crushing pressure on the material passing through the crushing chamber. The crushing load is of course distributed over the full face area of the movable jaw 18, and a substantial fraction thereof, which

may be as great as one-half of the entire crushing load, is taken by the lower end of said jaw, and hence by the lower toggle mechanism T₂. Since the latter, rather than acting as a rigid link, constitutes a "live" linkage system interposed between the lower end of the movable jaw, the frame and the intermediate drive shaft 28, it transmits a component of force, which is directly proportional to that fraction of the crushing load taken by the said lower end, to the shaft 28 and by virtue of the symmetrical disposition of the toggles, applies same to the opposite side of the shaft from the force applied thereto by the throw of the cam 32 in straightening out the upper toggle mechanism T₁. These opposing forces aforesaid have a squeezing action on the shaft 28, and hence neither force can result in any substantial deflection thereof, as is likely to result in shaft failures. Moreover, since the toggle mechanism T₂ itself effectively supplies a substantial thrust reaction for the force applied to the shaft 28 by the cam, or eccentric in causing the upper toggle mechanism to straighten-out, the main bearings 29, 30 are relieved to a substantial degree of the requirement of supplying such thrust reaction.

Upon engagement of the cam 32 with the cam followers 55 of the lower toggle mechanism T₂, said toggle mechanism is spread or straightened, and, as a consequence thereof, a substantial thrust is applied against the bottom of the moving jaw 18, causing it to move towards the fixed jaw 14 about the point of connection between the upper end of the movable jaw and the upper toggle T₁ acting as a fulcrum point, and in so doing, to supply the necessary crushing pressure. In this case, a substantial fraction of the crushing load is taken by the top end of the movable jaw 18, and transmitted through the upper toggle mechanism T₁ as a component of downward force on the shaft 28, i. e. as a force in opposition to the force exerted thereon by the action of the cam 32 in straightening the lower toggle mechanism T₂. Thus, the opposing force not only prevents upward deflection of the shaft but it also relieves the main bearings 29, 30 of the requirement of supplying the thrust reaction for the force which the cam applies to the shaft when straightening the lower toggle mechanism T₂.

Although the movable jaw is actuated alternately top and bottom, it will be understood that the mechanical advantage to the shaft is the same as if the jaw were moved simultaneously top and bottom, as by means of a double lobe cam to be later described. It will also be appreciated that, due to the unique suspension of the movable jaw 18 on rolling upright links 22, the movable jaw moves bodily with a substantially linear motion, even though it is actuated alternately top and bottom. Accordingly, no substantial vertical motion of the jaw takes place as is likely to cause excessive wear of the jaw faces, with the result that jaw wear is held to a minimum. Another advantage of a toggle system as described above is that it consists of two toggle mechanisms arranged symmetrically to opposite sides of the shaft 28, and having substantially similar size and weight. Thus, maximum balance as well as the favorable distribution of forces effective on the shaft consequent to alternate straightening of the toggle mechanism as explained above are assured.

Reverting to the two-part construction of the rearward end of the toggle arm 42 of the lower toggle mechanism T₂ and the yielding connection 49, 50, 51 between the two parts 42a, 42b thereof, such permit the lower end of the movable jaw 18 to "give" upon non-crushable material such as tramp iron being fed through the crushing chamber. It will be understood that when desired or for applications making same advisable, the aforesaid two-part block construction and yielding connection between the block parts may also be incorporated into the upper toggle mechanisms T₁.

Fig. 3 illustrates a modified form of jaw crusher according to the invention, which incorporates the novel

cam motion and toggle system for actuating the movable jaw, as previously described and as illustrated in Figs. 1 and 2, but differs therefrom in that the two toggle mechanisms T_1 and T_2 are simultaneously rather than alternately straightened, with the result that the movable jaw is actuated simultaneously top and bottom. Such may be simply achieved through the provision of symmetrical cams $32a$, $32b$, which are spaced apart substantially 180° on the drive shaft 28 , rather than the single-lobe cam 32 , as previously described.

By analysis, it will be observed that the symmetrical or double-lobe cams $32a$, $32b$ effect simultaneous straightening of the toggle mechanism T_1 , T_2 , resulting in substantially equal thrust forces being applied simultaneously, top and bottom, to the movable jaw 18 , causing it to move bodily and with substantially straight-line horizontal movement towards the fixed jaw 14 . Such results in a more or less equal distribution of the crushing loads being taken by the top and bottom of the movable jaw, and hence in the transmission of these crushing loads equally to the frame and to opposite sides of the drive shaft 28 to which latter they are applied in the form of equal and opposite forces. Hence, deflective forces applied to said shaft by cam or eccentric throw in conventional jaw crushers employing a single toggle system for translating cam or eccentric throw into jaw movement are effectively neutralized, since each of the two toggle mechanisms T_1 and T_2 supplies the thrust reaction for the other. It follows that the main bearings 29 , 30 are even more effectively relieved of the requirement for supplying any substantial thrust reaction than with the Figs. 1 and 2 form of toggle system. Moreover, since the movable jaw moves bodily with a substantially true straight-line motion, jaw wear resulting from relative vertical movement between the fixed and moving jaw, as in conventional jaw crushers, is completely eliminated.

Referring to Fig. 4, such illustrates the application of a toggle system as described above for translating throw of the cam 32 (or of the cams $32a$, $32b$) to the common movable jaw unit of a multiple jaw crusher. According to this modification, the fixed jaw assembly generally designated 70 comprises a transversely extending supporting plate 71 rigid with the frame end-member $13a$ and longitudinal plate-like members 72 extending substantially at right angles therefrom. Said members 72 are accordingly disposed parallel to the frame side-members 11 and 12 , and their rearward edges are stepped according to the number of jaw sets employed, the illustrated crusher construction being characterized by four such jaw sets. The riser portions $72a$ — $72d$ extending between the steps carry cross supports for hard metal wear plates $73a$ — $73d$, the latter constituting individual fixed crushing faces which are disposed at different vertical levels and in horizontally offset or staggered relation.

The movable jaw assembly generally designated 75 illustratively comprises a vertical supporting structure consisting of a pair of transversely extending structural members 76 , $76a$ rigidly affixed to one another as by horizontal spacing webs 77 , the aforesaid structural member 76 carrying plate-like members 78 extending longitudinally-forwardly therefrom. Said members 78 , like the members 72 , are disposed parallel to the frame side-members 11 , 12 and their forward edges are stepped complementally to the stepping of the forward edges of the said members 72 . The substantially vertical edge portions or risers (corresponding to risers $72a$ — $72d$) carry cross supports $79a$ — $79d$ for hard metal wear plates $80a$ — $80d$ constituting individual, movable crushing faces which pair with the aforesaid fixed crushing faces $73a$ — $73d$, thus to provide four sets of crushing jaws arranged at different elevations and with each lower jaw set being horizontally offset from the next higher jaw set. It will be seen that with each pair or set of jaw faces defining a crushing chamber, four independent crushing chambers are provided, but that all

four crushing chambers are arranged to be independently fed from a common hopper 81 .

The movable jaw assembly 75 may be and preferably is supported from the frame side members 11 , 12 for bodily reciprocatory travel by upright supporting links 22 as previously described, and said assembly is actuated toward and away from the fixed jaw assembly 70 by the aforesaid toggle system T_1 and T_2 , and by the retracting rods and springs, respectively, as employed in either of the Fig. 1 or Fig. 3 constructions.

Fig. 5 illustrates another form of crusher construction to which a toggle system according to the invention lends itself in practical and effective manner. In such a construction, the fixed jaw assembly generally designated 90 comprises a plurality of vertically disposed and roughly L-shaped plate members 91 backed by and extending longitudinally from the frame end member $13b$. At their rear edges, the plates 91 carry vertically spaced cross supports for the hard metal wear plates $92a$, $92b$, $92c$, constituting individual fixed crushing faces disposed at different vertical levels, of which the middle crushing face $92b$ is offset to one side and the lower crushing face $93b$ is offset to the other side of the upper crushing face $92a$.

The movable jaw assembly generally designated 96 includes a main cross member 97 from which vertical structural members 98 extend longitudinally in the direction of the fixed jaw, said members 98 carrying cross supports for hard metal wear plates $99a$, $99b$, $99c$, constituting movable crushing faces arranged to pair with the offset fixed crushing faces $92a$, $92b$, $92c$, respectively.

Consequent to the arrangement of the pairs or sets of jaws at different levels and the offsetting of the middle and lower jaw sets to opposite sides of the upper jaw set, all as aforesaid, there is provided a substantial space directly beneath the discharge end of the crushing chamber formed by the upper jaw set $92a$, $99a$ and between the middle and lower jaw sets. According to the invention, a sizing screen 100 is mounted in said space, being carried by longitudinal-forward extensions of the structural members 98 of the movable jaw assembly, said extensions carrying cross plates 101 , 102 , to the top edges of which the screen 100 is secured.

The sizing screen 100 has the shape of an inverted V in longitudinal section, and it is dimensioned and arranged so that its sides slope toward the middle and lower jaw sets, respectively. The apertures of the wire mesh or other material from which the sizing screen is fabricated are of such size that material which has been adequately reduced by the action of the upper jaw set $92a$, $99a$ will pass through the screen, from which it falls on to a conveyor 104 located so as to receive the discharge from all three jaw sets. The material which has not been reduced sufficiently is diverted sidewardly by the screen to either the middle or lower jaw sets, from whence, following further reduction, it falls on to the conveyor 104 .

As with the Fig. 4 modification, the movable jaw assembly 96 according to the Fig. 5 construction, is supported for bodily reciprocatory movement from the frame side members 11 and 12 as by the aforesaid upright links 22 , and is bodily actuated toward the fixed jaw assembly 90 by the toggle system T_1 , T_2 of either the Fig. 1 or Fig. 3 forms, and throughout its return stroke or travel by the retracting rods and springs as aforesaid.

In operation of a crusher according to Fig. 5, the rock or other solid material is initially delivered to the crushing path defined by the crushing faces $92a$, $99a$, the discharge therefrom falling on to screen 100 . Adequately crushed material passes through the screen on to the conveyor 104 . However, material requiring further reduction is diverted to either the middle or lower crushing chambers as defined by the jaw faces $92b$, $99b$, and $92c$, $99c$, the material discharging from these further paths also falling on to the conveyor 104 . Since the sizing screen 100 is carried by the movable jaw assembly 96 , it par-

takes of movement therewith, so that screening action is promoted.

Without further analysis, it will be appreciated that the invention achieves in simple and effective manner the desirable objectives therefor outlined in the foregoing. In all of the illustrated crusher forms, the crushing load is transmitted back to the driving shaft, and distributed as forces acting on the shaft from its opposite sides at the same time, whereby they squeeze the shaft rather than imposing defective action thereon. It follows that the main or drive shaft bearings are relieved to a substantial degree of the requirement of supplying the reaction for the force or forces applied to the shaft consequent to eccentric or cam throw, since this reaction is supplied instead by the crushing load acting through one or both of the toggle mechanisms T_1, T_2 .

Also, a cam motion system according to the invention lends itself to a wide variety of crusher designs wherein bodily linear or substantially linear motion of the movable jaw rather than a swinging movement is desirable. Thus, in addition to its application to a conventional or single jaw crusher design as illustrated in Figs. 1 and 3, the eccentric motion system of the invention may be applied to the so-called multi-jaw crushers, including such a crusher construction employing a sizing screen arranged to promote a highly efficient crushing action, as by diverting material leaving one jaw set and which requires further reduction to one or more jaw sets wherein further reduction is obtained.

As many changes could be made in carrying out the above constructions without departing from the scope of the invention, it is intended that all matter contained in the above description or shown in the accompanying drawings shall be interpreted as illustrative and not in a limiting sense.

This application is a continuation-in-part of application Serial No. 208,277, filed January 29, 1951, now abandoned.

I claim:

1. A jaw crusher comprising, in combination, a frame, a fixed jaw rigid with said frame, a movable jaw, rolling-link means supporting the movable jaw from the frame for substantially bodily reciprocatory movement toward and away from the fixed jaw, means for actuating said movable jaw toward the fixed jaw including a drive shaft, cam means thereon, and a toggle mechanism actuatable by the cam means and adapted during straightening to apply an actuating thrust on said movable jaw, means for transmitting a portion of the crushing load developed on actuation of the movable jaw to the drive shaft as a force opposing the force exerted on the shaft by said cam means in straightening the toggle mechanism, and means for actuating the movable jaw away from the fixed jaw.

2. A jaw crusher comprising, in combination, a frame, a fixed jaw rigid with said frame, a movable jaw, rolling-link means supporting the movable jaw from the frame for substantially bodily reciprocatory movement toward and away from the fixed jaw, means for actuating said movable jaw towards the fixed jaw including a drive shaft, a toggle system operative between the frame and the upper and lower ends of the movable jaw and cam means on the drive shaft for actuating said toggle system, said toggle system being constructed and arranged so as to transmit portions of the crushing load developed upon movement of the movable jaw to the drive shaft as forces acting on said shaft from opposite sides thereof, and means for actuating the movable jaw away from the fixed jaw.

3. A jaw crusher as set forth in claim 2, wherein said toggle system comprises a pair of toggle mechanisms symmetrically disposed to the opposite side of the drive shaft and being operatively connected to the upper and lower ends of said movable jaw, respectively.

4. A jaw crusher comprising, in combination, a frame, a fixed jaw rigid with the frame, a movable jaw, means supporting the movable jaw from the frame for substan-

tially bodily reciprocatory movement toward and away from the fixed jaw, means for actuating said movable jaw towards the fixed jaw including a drive shaft, upper and lower toggle mechanisms arranged symmetrically to opposite sides of the shaft and being operatively connected to the frame and to the upper and lower ends of the movable jaw, respectively, and cam means carried by said shaft for effecting simultaneously straightening of said toggle mechanisms, each said toggle providing a live linkage system for translating a portion of the crushing load developed upon actuation of the movable jaw into a component of force effective on said drive shaft in a direction opposite that of the force exerted thereon by the other toggle mechanism, and means for actuating the movable jaw away from the fixed jaw.

5. A jaw crusher comprising, in combination, a frame, a fixed jaw rigid with said frame, a movable jaw, means supporting the movable jaw for substantially bodily reciprocatory movement toward and away from the fixed jaw, means for actuating said movable jaw toward the fixed jaw including upper and lower toggle mechanisms operatively connected to the frame and to the upper and lower ends of the movable jaw respectively, and a drive shaft disposed intermediate said toggle mechanisms for actuating the latter simultaneously, the construction and arrangement being such that in addition to actuating the movable jaw, said toggle mechanisms are each effective to translate the portion of the crushing load taken by the end of the movable jaw to which it is connected into a force acting on said shaft in opposition to the force exerted thereon through the other toggle mechanisms, and means for actuating the movable jaw away from the fixed jaw.

6. In a crusher, a frame, a fixed jaw rigid with the frame, a movable jaw, rolling-link means mounting said movable jaw from said frame for substantially equal movement, top and bottom, toward the fixed jaw, toggle means operative between the frame and each of the top and bottom, respectively, of the movable jaw for imparting movement as aforesaid to said movable jaw, and a single drive shaft for actuating said toggle means.

7. A crusher as set forth in claim 6, wherein said toggle means and drive shaft are cooperatively arranged so as to apply an actuating force to the top of the movable jaw during one portion of the rotation of the drive shaft and to the bottom of the movable jaw during another portion of the rotation of the drive shaft.

8. A crusher as set forth in claim 6, wherein said toggle means and drive shaft are cooperatively arranged so as to actuate the movable jaw substantially equally and simultaneously, top and bottom.

9. In a crusher, a frame, a fixed jaw rigid with said frame, a movable jaw, and means for actuating the movable jaw towards the fixed jaw comprising a single drive shaft having toggle actuating means thereon and toggle means operative between the top and bottom of the movable jaw and said frame and actuatable by said toggle actuating means, said toggle means being positioned so as to be operative to divide the crushing load into substantially equal quantities and to translate said quantities into forces acting simultaneously on said shaft from substantially opposite sides thereof.

10. In a crusher, a frame, a pair of opposed crushing jaws, rolling-link means mounting one of jaws from said frame for bodily movement in a horizontal plane, and means for actuating said movable jaw top and bottom towards and away from the other jaw.

11. In a crusher, a frame, a pair of opposed crushing jaws, means mounting one of said jaws from said frame for bodily movement in a horizontal plane comprising a pair of vertically disposed load-supporting links operative between the frame sides and said one jaw and having rolling engagement therewith, and means for actuating said one jaw, top and bottom, towards and away from the other jaw.

12. In a crusher, a frame, coacting jaws supported on said frame for relative reciprocatory movement toward and away from one another, means including a toggle mechanism operative between the frame and one of said jaws, and toggle straightening means for imparting such relative movement to the jaws, said toggle mechanism including a pair of articulated toggle arms and said toggle straightening means including a thrust-transmitting member for transmitting thrust to one of said toggle arms adjacent its articulated end, said thrust-transmitting member and said one toggle arm meeting along a plane surface which is inclined to the direction of thrust transmitted to said one toggle arm, whereby to permit relative lateral displacement of said thrust transmitting member and said one arm upon the occurrence of abnormal thrust, and resilient means operative between said thrust-transmitting member and said one toggle arm for resisting such lateral displacement.

13. In a crusher, a frame, a fixed jaw rigid with said frame, a movable jaw, rolling-link means mounting the movable jaw for substantially bodily reciprocatory movement toward and away from the fixed jaw, means for actuating the movable jaw as aforesaid, said jaws mounting a plurality of pairs of cooperating jaw faces, said pairs being arranged at different vertical levels and being laterally offset one from the other.

14. A crusher as set forth in claim 13, wherein said pairs of jaw faces are arranged in step relation.

15. A crusher as set forth in claim 13, wherein three pairs of jaw faces are provided, the intermediate pair being disposed to one side and the lower pair being disposed to the other side of the upper pair, and wherein a screen is disposed in the path of crushed material from the upper pair of jaw faces and is constructed and arranged so as to divert said crushed material failing to pass the screen to one or the other of the intermediate and lower pairs of jaw faces.

16. A crusher as set forth in claim 15, wherein the screen is carried solely by the movable jaw and partakes of its movement.

17. A crusher for rock and like solids comprising, in combination, a frame, coacting jaws supported on said frame for relative reciprocating movement toward and away from each other, and mechanism mounted on said frame for imparting such relative movement to said jaws, said mechanism comprising a pair of toggles located in spaced relation, said toggles being operatively connected to one of said jaws at spaced points and reacting against said frame to impart reciprocatory movement to said jaw, a shaft supported for rotation on said frame, said shaft being disposed intermediate said toggles, and a cam on said shaft operatively connected with said toggles, said cam being so shaped as to effect concurrent straightening of said toggles, whereby thrust on said shaft is substantially balanced.

18. A crusher for rock and like solids comprising, in combination, a frame, coacting jaws supported on said frame for relative reciprocating movement toward and away from each other, jaw faces supported on said jaws in opposed relation to provide a path for the flow of solids therebetween, and mechanism mounted on said frame for imparting relative movement to said jaws, said mechanism comprising a pair of toggles located in spaced relation, the pivotal axes of one toggle being parallel to the pivotal axes of the other, said toggles being operatively connected to one of said jaws at spaced points and reacting against said frame to impart reciprocatory movement to said jaw, a shaft supported for rotation on said frame with its axis parallel to the pivotal axes of said toggles, said shaft being disposed intermediate said toggles, and a symmetrical radial cam on said shaft engaging said toggles to effect straightening thereof and a consequent distribution of the crushing load through said toggles to opposite sides of said shafts.

19. A crusher for rock and like solids comprising, in

5 combination, a frame, coacting jaws mounted on said frame, means supporting at least one of said jaws for substantially rectilinear bodily movement toward and away from the other of said jaws, and mechanism operatively connected to said movable jaw at spaced locations on the latter for applying at each of such locations a thrust of substantially the same amplitude and intensity, said means comprising a plurality of toggles, each reacting at one end against said movable jaw at one of said locations, and means carried by said frame, disposed intermediate said toggles, and operatively engaging said toggles to exert thrust on said toggles in opposite directions to effect straightening thereof.

10 20. A crusher for rock and like solids comprising, in combination, a frame, coacting jaws mounted on said frame, means supporting at least one of said jaws for substantially rectilinear bodily movement toward and away from the other of said jaws, and mechanism operatively connected to and acting between said frame and said movable jaw at spaced locations on the latter for applying at each of such locations a thrust of substantially the same amplitude and intensity, said mechanism including a drive shaft, and means for delivering the crushing load resulting upon movement of said one jaw 25 to opposite sides of the shaft.

21. A crusher for rock and like solids comprising, in combination, a frame, coacting jaws mounted on said frame, opposed jaw faces supported on said jaws, said faces converging downwardly to provide therebetween 30 a narrowing path for the downward discharge of solids, means supporting one of said jaws for substantially rectilinear bodily movement toward and away from the other of said jaws, said means comprising generally upright supporting links, one adjacent each side of said movable jaw, each link having a rolling connection at one of its ends with said movable jaw and at the other of its ends with said frame, and mechanism operatively connected to said movable jaw at spaced locations on the latter for applying at each of such locations a thrust of substantially the same amplitude and intensity, said means comprising a plurality of toggles, each reacting at one end against said movable jaw at one of said locations, and means carried by said frame operatively engaging said toggles to effect straightening thereof, said last named means comprising an eccentric device supported for rotation on said frame.

35 22. A crusher for rock and like solids comprising, in combination, a frame, coacting jaws mounted on said frame, opposed jaw faces supported on said jaws, said faces converging downwardly to provide therebetween 40 a narrowing path for the downward discharge of solids, means supporting one of said jaws for substantially rectilinear bodily movement toward and away from the other of said jaws, said means comprising generally upright load supporting links supporting said one jaw from below, and mechanism operatively connected to said movable jaw at spaced locations on the latter for applying a thrust at each of such locations.

45 23. A crusher for rock and like solids comprising, in combination, a frame, coacting jaws mounted on said frame, means supporting at least one of said jaws for substantially rectilinear bodily movement toward and away from the other of said jaws, and mechanism operatively connected to said movable jaw at spaced locations 50 on the latter for applying a thrust at each of such locations, said means comprising a plurality of toggles, each reacting at one end against said movable jaw at one of said locations, and means carried by said frame and operatively engaging said toggles to effect straightening thereof, said last named means comprising an eccentric device supported for rotation on said frame and disposed intermediate said toggles.

55 24. A crusher for rock and like solids comprising, in combination, a frame, coacting jaws supported on said frame for relative reciprocating movement toward and

away from each other, and mechanism mounted on said frame for imparting such relative movement to said jaws, said mechanism comprising a toggle, and devices applying pressure to said toggle to straighten the latter, said devices including a pair of thrust transmitting members having engaged surfaces defining a plane inclined to the direction of thrust transmitted through said members, whereby relative lateral displacement of said members occurs in response to excessive thrust, and resilient means acting between said members to resist such lateral displacement.

25. A crusher for rock and like solids comprising, in combination, a frame, coating jaws supported on said frame for relative reciprocating movement toward and away from each other, mechanism mounted on said frame for imparting such relative movement to said jaws, a vertical series of pairs of opposed jaw faces supported on said jaws and being arranged in laterally offset relation to provide a plurality of downwardly directed paths for the flow of solids between said pairs of jaw faces, and a common hopper for supplying solids directly to all said paths.

26. A crusher for rock and like solids comprising, in combination, a frame, coating jaws mounted on said frame, means supporting at least one of said jaws for substantially rectilinear bodily movement toward and away from the other of said jaws, mechanism mounted on said frame for imparting such relative movement to

said jaws, a plurality of pairs of coating jaw plates mounted on said jaws to provide between each pair of plates a downwardly directed path for solids, one of said pairs of plates being disposed above and discharging 5 crushed solids into others of said pairs of plates, and a screen in the path of the discharging solids and interposed between said first named pair of plates and said others of said pairs of plates to divert adequately crushed material from the latter, said screen being carried by and 10 moving with said movable jaw, and being inclined downwardly in opposite direction toward each of the others of said pairs of plates.
